UNITED STATES PATENT OFFICE.

WALTER R. PHILLIPS, OF KANSAS CITY, MISSOURI.

MATTRESS-MAKING APPARATUS.

1,244,773.

Specification of Letters Patent. Patented Oct. 30, 1917.

Application filed June 23, 1916. Serial No. 105,384.

To all whom it may concern:

Be it known that I, WALTER R. PHILLIPS, a citizen of the United States, residing at Kansas City, in the county of Jackson and State of Missouri, have invented a certain new and useful Improvement in Mattress-Making Apparatus, of which the following is a specification.

My invention relates to improvements in 10 mattress making apparatus.

The object of my invention is to provide an apparatus by which edge rolls on mattresses may be formed.

Another object of my invention is to provide 15 a novel roll forming apparatus with which an edge roll may be formed on a mattress which will be symmetrical in form.

My invention provides further novel 20 means for stitching the mattress ticking between the edge roll and the body of the ticking.

My invention provides still further a 25 novel core, around which the ticking is formed into a tube, the core comprising a plurality of members adapted for separate removal after the ticking has been formed into a tube and stitched together on the core.

Still another object of my invention is to 30 provide releasable clamping means adapted to coöperate with the core for forming the tube in the ticking and releasably holding the ticking in position for being stitched together.

The novel features of my invention are 35 hereinafter fully described and claimed.

In the accompanying drawings, which illustrate the preferred embodiment of my invention.

Figure 1 is a central longitudinal section 40 of the core and clamping mechanism shown in the clamping position, together with a needle mounted in the stitching position.

Fig. 2 is a perspective view of a portion 45 of a mattress in a condition suitable for manipulation with the roll forming mechanism.

Fig. 3 is an enlarged cross section on the line 3—3 of Fig. 1.

Fig. 4 is an enlarged cross section on the 50 line 4—4 of Fig. 1.

Fig. 5 is an enlarged cross section showing the clamping members in the clamping position on the core.

Fig. 6 is an enlarged cross section showing 55 the clamping members in the open position and partly detached from the core.

Fig. 7 is a cross section of a portion of a mattress showing one of the completed rolls.

Fig. 8 is a perspective view of the clamping members shown in the open position, 60 central portions being broken away.

Fig. 9 is a perspective view of the core partly broken away, with the members interlocked with each other.

Fig. 10 is a view of a needle adapted to be 65 used in connection with the apparatus.

Fig. 11 is a longitudinal sectional view on the line 11—11 of Fig. 5.

Fig. 12 is a perspective view of a mattress having the edges formed into rolls. 70

Similar reference characters designate similar parts in the different views.

In forming and filling rolls at the edges of a mattress, my invention provides a removable core, around which the ticking adjacent to the corner to be formed is held 75 clamped by my improved clamping mechanism until the stitching, hereinafter described, is effected. After the tube has been thus formed from the ticking, the clamping 80 mechanism is removed and also the core, a filling tube, not shown, being substituted for the latter, the filling tube containing a roll of filling material which is left deposited in the roll casing upon the dismemberment and 85 removal of the filling tube.

The core is longitudinally centrally divided and comprises two longitudinal members 1 and 2, each of which is substantially semi-cylindrical. The member 2 at one end 90 is provided with a dove-tail projection 3, Figs. 1 and 4, adapted to be slid endwise into a corresponding recess in the adjacent end of the member 1. The opposite end of the member 1 is provided with a longitudinal 95 dove-tail projection 4 adapted to be slid into a corresponding recess in the adjacent end of the member 2, Figs. 1, 3 and 9. By means of this dove-tail connection, the members 1 and 2 are releasably locked and held 100 together in their operative position. The member 2 at one end, Fig. 1, is provided with a knob handle 5 by means of which the member 2 may be slid endwise into and out of locked engagement with the member 1. 105

The periphery of the member 1 is provided with a plurality of radially extending projections 6, disposed in a longitudinal row, Figs. 1, 6, 9 and 11. Each projection 6 is provided in its outer end with a notch 7 110 adapted to receive longitudinally therethrough a long needle 8, Figs. 1, 5, 10 and 11,

which is adapted to carry through said notches 7 a stitching cord 9, Figs. 1 and 7.

Each notch 7 is sufficiently contracted at its outer end, Fig. 6, to prevent lateral removal therethrough of the needle 8, but which will permit the lateral removal therethrough of the stitching cord 9 after the ticking has been stitched thereby.

The core assembled as shown in Fig. 9, is 10 inserted in the ticking 10 parallel with and adjacent to the edge which is to be formed into a roll. To permit of such insertion, a corner 11, Fig. 2, of the ticking at each end of the edge of the mattress to be formed, is 15 left unstitched.

For the purpose of clamping the ticking 10 in tubular form around the core, I provide two tubular clamping members 11 and 12, Figs. 3, 4, 5, 6 and 8, which are hinged together at two of their adjacent edges by a longitudinal pintle 13. Each member 11 and 12 is semi-circular in cross section, so that when in the clamping position, shown in Fig. 5, they will clamp the ticking 10 tightly against the periphery of the cylindrical core.

The clamping member 11 is provided adjacent to its respective ends with two handles 14 disposed respectively adjacent to 20 two handles 15 with which the member 12 is provided.

Pivoted respectively to the handles 15 are two arcuate toothed members 16 which are respectively adapted to engage two teeth 17 35 respectively provided on the handles 14, Figs. 5 and 6.

Respectively secured to the handles 14 are two springs 18 which normally force the members 16 into engagement with the 40 teeth 17.

The teeth 17 and the teeth 19, of the members 16, are so shaped as to be lockingly engaged so as to hold the clamping members 11 and 12 in the clamping position shown in 45 Fig. 5.

The free edges of the clamping members 11 and 12 are provided each with a plurality of projections 20 adapted to enter alternate spaces between the projections 6 when 50 the clamping members 11 and 12 are in the clamping position, as shown in Figs. 1 and 5. The projections 20 are provided each with a recess 21 adapted to register with the recesses 7 when the clamping members are 55 in the clamping position, as shown in Fig. 11.

The member 11 is provided adjacent to its ends respectively with two inwardly radially extending arms 22, Figs. 1, 5, 6 and 8, 60 which in the clamping position respectively enter two slots 23, Fig. 9, provided in the member 1. These arms hold the clamping members from circumferential movement on the core.

65 In the operation of my invention, the core

members 1 and 2 are placed, in their interlocked relationship with each other, in the mattress adjacent to and parallel with the edge which is to be formed into a roll, with the projections 6 extending inwardly and downwardly, as shown in Fig. 6, and with the ends of the core projecting beyond the edges of the mattress, as shown in Fig. 1.

The clamping members 11 and 12 are then applied to the exterior of the ticking 10, the handles 14 and 15 being swung toward the closed position, shown in Fig. 5, with the arms 22 extended into the recesses 23. The handles 14 and 15 are then swung upwardly, prior to the members 11 and 12 being tightly clamped, so that the edge seam 24 of the mattress, Fig. 7, will be at the under side of the roll when the latter is completed. The handles 14 and 15 are now compressed to the fully closed position, in which they will be releasably held by the toothed members 16, the projections 20 of the members 11 and 12 passing in opposite directions between the projections 6, and thereby forcing opposite portions of the ticking, designated by 25, Fig. 11, alternately in opposite directions between the projections 6 and across the path of movement of the needle 8.

The needle 8 may now be passed through the notches 7 and 21, thereby drawing the 95 stitching cord 9 through the notches 7 and 21 and through the portions 25 of the ticking 10 which overlap the path of travel of the needle 8.

The opposite sides of the tube which has 100 been formed in the ticking along the edges of the mattress and around the core, are now stitched together. The members 16 are now released from the teeth 17, the handles 14 and 15 swung apart, and the clamping 105 members 11 and 12 detached from the core.

The handle 5 of the core member 2 is now pulled outwardly, thereby withdrawing the member 2 from engagement with the member 1 and from the tube formed in the ticking. The member 1 is then forced outwardly laterally, so as to detach the projections 6 from the ticking, the stitching cord being withdrawn laterally, at the same time, from the notches 7 of said projections.

115 The member 1 may now be removed endwise from the tube of ticking.

I do not limit my invention to the structure shown and described, as modifications, within the scope of the appended claims, 120 may be made without departing from the spirit of my invention.

What I claim is:—

1. In a mattress making apparatus, a core, 125 means for clamping a portion of the ticking of a mattress around said core with opposite portions of the ticking overlapping a longitudinal straight line, and means by which stitching material may be extended through said overlapping portions.

2. In a mattress making apparatus, a longitudinally divided core provided with a longitudinal series of projections spaced apart and provided each with a notch in its outer end adapted to receive therethrough a needle and a stitching cord attached thereto. 70
3. In a mattress making apparatus, a core provided with a longitudinal series of projections spaced apart and having each in its outer end a notch adapted to receive therethrough a needle and a stitching cord attached thereto, the outer end of said notch being contracted so as to retain the needle in the notch but which permits the withdrawal laterally from the notch of the cord. 75
4. In a mattress making apparatus, a core provided with a longitudinal series of projections spaced apart and having each in its outer end a notch adapted to receive therethrough a needle and a stitching cord, and means for clamping the ticking of a mattress around said core and for overlapping in opposite directions alternately portions of said ticking between said projections. 80
5. In a mattress making apparatus, a core provided with a longitudinal series of projections each having in its outer end a notch adapted to receive longitudinally therethrough a needle and a stitching cord, and two clamping members pivoted together and having means for clamping the ticking of a mattress around said core and for forcing opposite portions of said ticking alternately in opposite directions between said projections and into positions in which said needle when inserted longitudinally through said notches will pass through the portions of the ticking disposed between said projections. 85
6. In a mattress making apparatus, a core provided with a longitudinal series of projections, each having in its outer end a notch adapted to receive longitudinally therethrough a needle and a stitching cord, and two clamping members pivoted together and adapted to clamp the ticking of a mattress around said core and provided respectively at their outer edges with projections having end notches and adapted to support opposite portions of said ticking in opposite directions alternately between said projections of the core, the notches of the core projections and of the clamping members being in alignment in the clamping position of the clamping members. 90
7. In a mattress making apparatus, a cylindrical core comprising two longitudinal members releasably interlocked, one having on its periphery a series of projections each having in its outer end a notch, and two clamping members hinged together and adapted to embrace said core and having at their outer edges respectively projections having end notches and adapted to pass between the projections of the core in opposite directions and in an alternate manner, the notches of the core projections and the clamping member projections being in alignment in the clamping position of the clamping members and adapted to receive therethrough longitudinally a needle and a stitching cord, one of the clamping members having means for releasably engaging with the core so as to hold the clamping members, when in the clamping position from circumferential movement on the core. 95
8. In a mattress making apparatus, a core, and clamping means arranged to releasably embrace the core and adapted to clamp around the core the ticking of a mattress, said core and clamping means having means cooperating with each other for forcing and holding opposite portions of the ticking into positions in which they will be alternately disposed and in longitudinal alignment with each other so as to be pierced by a needle inserted in a straight line through the several alternately disposed portions. 100
9. In a mattress making apparatus, a core comprising two longitudinal segmental members having means for being releasably interlocked together, one of said members having a longitudinal row of projections provided with needle guiding means, two clamping members adapted to clamp around the core the ticking of a mattress, said two clamping members being provided with means for forcing opposite portions of the ticking between said projections and in alternate relationship to each other and in position for being pierced by a needle inserted through said guiding means, and releasable means for holding said clamping members in the clamping position. 105
10. In a mattress making apparatus, means for forming into a tube a portion of the ticking of a mattress, and means for disposing opposite portions of the tube in alternate relationship to each other and in longitudinal alignment with each other, whereby they may be stitched together with a straight stitch. 110
11. In a mattress making apparatus, a core adapted to have a portion of the ticking of a mattress formed around the core into a tube, and means for disposing opposite portions of the tube in alternate relationship to each other and in longitudinal alignment with each other with respect to the core, whereby said portions may be stitched together with a straight stitch. 115
12. In a mattress making apparatus, a core adapted to have a portion of the ticking of a mattress formed into a tube around the core, and means for folding alternate opposite portions of the tube and disposing them in longitudinal alignment with each other with respect to the core, whereby said folded alternate portions may be stitched together with a straight stitch. 120
13. In a mattress making apparatus, a 130

core comprising two members having means for being releasably interlocked side by side, means for clamping the ticking of a mattress around said core and for releasably holding it so clamped with the clamped portion retained in the form of a longitudinally divided tube, and means for stitching together opposite adjacent portions of said tube.

14. In a mattress making apparatus, a

longitudinally divided core comprising two members adapted to be arranged side by side, and clamping means for forming the ticking of a mattress around said core and co-operating therewith for bringing opposite portions of the ticking into stitching relationship with each other.

In testimony whereof I have signed my name to this specification.

WALTER R. PHILLIPS.
